FABRIC FOLDING MACHINE

René H. Toubhans, San Leandro, Calif.

Application February 3, 1947, Serial No. 725,991

10 Claims. (Cl. 153—28)

1

This invention relates to a machine for forming a fold or hem on one or both edges of a strip or a piece of fabric, and particularly on wire fabric such as used for window screening and the like.

The object of the present invention is generally to improve and simplify the construction and operation of machines of the character described; to provide a machine which will gradually bend and fold one or both side edges of a strip or piece of fabric as the fabric in flat form passes through the machine; to provide a machine which will form a single or multiple fold on one or both edges of the fabric; to provide a machine in which the bending and folding action is continuous and capable of high speed; to provide a machine through which the fabric to be folded is continuously and positively fed; to provide a machine which insures a fold of uniform or constant width; and further to provide a machine which is adjustable to receive fabric of different widths.

The machine is shown by way of illustration in the accompanying drawings in which:

Fig. 1 is a perspective view of the machine;

Fig. 2 is a plan view of the right-hand unit of the machine as seen in Figure 1;

Fig. 3 is an elevation of the outside of the unit shown in Fig. 2;

Fig. 4 is an elevation of the inside of the unit shown in Fig. 2;

Fig. 5 is an enlarged cross-section taken on line V—V of Fig. 2;

Fig. 6 is an enlarged cross-section taken on line VI—VI of Fig. 2;

Fig. 7 is an enlarged cross-section taken on line VII—VII of Fig. 2;

Fig. 8 is an enlarged cross-section taken on line VIII—VIII of Fig. 2;

Fig. 9 is an enlarged cross-section taken on line IX—IX of Fig. 2;

Fig. 10 is an enlarged cross-section of a table top showing the rack bars in gear whereby the width of the table is adjusted; and

Fig. 11 is a side elevation showing a modified form of fabric gripping mechanism.

Referring to the drawings in detail, and particularly Figures 1, 2, 3 and 4, A indicates an angle iron frame supported by legs 2. Forming a top for the frame is a table surface 3 having side extensions 4 and 5 which are laterally adjustable. The extensions 4 and 5 are supported by the table surface 3 as they overlap the same, and also by arms 4a and 5a, of which there may be a suitable number depending upon the length of the table (see Fig. 10). Each arm is provided with a tooth and rack bar and these bars engage a gear pinion 6 secured on a shaft 7 which is journaled under the table surface and extends longitudinally thereof. By applying a hand

2

crank to the end of the shaft 7 and rotating it, the side extensions 4 and 5 of the table may be moved inwardly or outwardly with relation to the central table surface 3, thereby varying the width of the table as a whole to take care of fabric of different widths.

Suitably supported by the frame A is a motor 8 which through a belt 9 drives a reduction gear drive 10 of standard construction. A tubular drive shaft extending transversely of the reduction gear drive case carries a pair of shafts 14 which telescope with relation thereto and which are also splined thereto. These shafts, that is the shafts 14, form drive shafts whereby the fabric folding machines are driven.

There are two fabric folding machines B and C supported one on each side of the table, but as each machine is identical in construction and operation, the description of one will suffice.

Referring now to Figs. 2 to 9 inclusive, 16 indicates a bar which is secured to the table extension 5 by means of a pair of legs 17. Spaced from the bar 16 and disposed above the same is a second bar 16a which is secured to bar 16 by spacer bolts 16b at each end (see Fig. 4). The bars 16 and 16a supported by the legs 17 constitute a frame which forms a support for five pairs of horizontally disposed shafts indicated at 18 and 18a, 19 and 19a, 20 and 20a, 21 and 21a, and 22 and 22a. These shafts are best shown in Figs. 5 to 9, inclusive. Shaft 18 carries a grooved roller 23 and shaft 18a also carries a grooved roller such as indicated at 24. Shaft 19 carries a grooved roller 25, and shaft 19a carries a grooved roller 26, the inner end of which is provided with an annular projecting flange 26a. Shaft 20 carries a grooved roller 27, and in addition thereto a beveled gear 28 which meshes with a beveled gear 29 journaled about a vertically disposed shaft secured between the frame bars 16 and 16a. The gear 28 is provided with an annular projecting flange 30 and this overlies one end of a grooved roller 31 secured on shaft 20a. Shaft 21 carries a grooved roller 32 and shaft 21a carries a grooved roller 33 which is provided with an annular flange 34. Shaft 22 carries a roller 35 having an annular flange 36 at one end and a beveled gear 37 at the opposite end. This gear meshes with a beveled gear 38 journaled about a vertical shaft secured between the frame bars 16 and 16a and the last-named beveled gear is provided with an annular flange 38a which partially overlies a grooved roller 39 secured on the shaft 22a.

The grooved and flanged rollers are all secured on one end of the shafts, while the opposite ends of these shafts, that is shafts 18, 18a, 19, 19a, 20, 20a, 21, 21a, 22 and 22a, have secured thereto sprocket gears such as shown at 40 and 41. All 60 of the sprocket gears intermesh with a common

sprocket chain 42 and this is carried by a pair of sprocket gears 43 and 44 disposed one at each end of the frame (see Fig. 4), the sprocket gear 43 being a driving gear as it is secured on the driving shaft 14 while the sprocket gear 44 is an idler gear and is secured on an idler shaft 15. Also secured on the driving shaft 14 is a pulley 45 and journaled at the opposite end of the frame is a pulley 46. The pulleys 45 and 46 carry an endless belt made of flexible steel or like material, said belt being indicated at 47 and said belt carrying closely spaced outwardly projecting pins 48, the function of which will hereinafter be described. The belt 47 passes over the grooved rollers 24, 26, 31, 33 and 39 and under the grooved rollers 23, 25, 27, 32 and 35. The pins 48 project into the groove formed in these rollers while the belt itself rides in the groove of the rollers upon which it rests. This groove is rather shallow so that pressure may be applied by the upper rollers against the belt 47 when the machine is in operation.

In actual operation let it be supposed that it is desired to form a double fold at opposite sides of a piece or strip of fabric screen such, for instance, as wire screen used for screening windows. If that is the case, the table extensions 4 and 5 are first adjusted to conform to the width of the fabric or screen material to be folded and when it is properly adjusted, the screen is laid on the table and fed in the direction of arrow D so that the forward end will enter between the rollers carried by the respective folding units indicated at B and C. The screen thus moved forwardly will first enter between the rollers 23 and 24 (see Fig. 5) where the pins 48 will pass through the wire screen and thereby positively grip and secure the screen and also feed it through the machine as belt 47 is driven by its driving pulley. The screen while passing between the rollers 23 and 24 is flat. When the screen approaches the rollers 25 and 26 (see Fig. 6), it comes into engagement with the annular flange 26a. This obviously bends the side edge of the screen to assume the right angular position indicated at 50. As the screen is further advanced, it enters between the rollers 27 and 31, and as the annular flange 30 on the beveled gear 29 partially overlies the roller 31, it will engage the right angular bent edge of the screen 50 and fold it flat against the screen body as shown at 51. Further advance of the screen brings it between rollers 32 and 33, and as the roller 33 is provided with an annular flange 34, it will again bend the edge of the screen upwardly to assume the right angular position shown at 52, and when the screen finally enters between the rollers 35 and 39, it will engage the overlying flange 38a of the beveled gear 38, thereby again folding the screen flat against itself as shown at 53. A single fold is formed at the point 51 (see Fig. 7) while a double fold is formed at the point 53 (see Fig. 9). If a single fold is desired, the rollers shown in Figs. 8 and 9 may be eliminated, but if a double or multiple fold is desired, these rollers must be employed.

Inasmuch as there are two folding machine units B and C, and as these units are identical in construction and operation, it is obvious that either a single or a multiple fold will be formed on opposite sides of the screen material as it passes through the machine. It should also be obvious that each fold whether single or multiple will be uniform in width throughout the length of the screen or fabric material as the fabric is held

firmly in place by the pins 48 of the belt 47 while passing through the machine. Furthermore, as each folding unit is driven at the same speed and all rollers are of the same diameter, it is obvious that each side of the fabric will be fed at the same rate and a uniform result is insured. That is, the first bending operation shown at 50 in Fig. 6 is not completed until the screen material reaches the center of the roller 26. That is, the screen material will contact the flange 26a prior to reaching center position, and as such the folding is gradual and is completed when the center of the roller 26 is reached. The bending operation at 51 is the same, and this is also true of the bending or folding operations shown at 52 and 53. Due to this gradual bending or folding operation, it is possible to feed the screen or fabric material continuously and at comparatively high speeds. In Figs. 1, 2 and 5 to 9 inclusive, a feeding belt 47 having pins 48 is shown for the purpose of gripping and feeding the fabric material while passing through each folding unit. In Fig. 11 a slight modification is shown. In this instance steel belts similar to the belts 47 are employed, but they are faced with rubber as indicated at 55. This rubber is of a compressible nature and the wire screen may thus be tightly gripped and fed by the rubber faced belts 55, and while this and other features of the machine have been more or less specifically described and illustrated, it should be understood that changes may be resorted to within the scope of the appended claims and that the materials and finish of the several parts employed may be such as the experience or judgment of the manufacturer may dictate or varying conditions or uses may demand.

Having thus described my invention, what I claim and desire to secure by Letters Patent is:

1. In a machine of the character described, a support to receive a fabric material to be folded, a continuously moving member extending longitudinally of the support, means on the member for interengaging the fabric material to move it with the member, a rotatable member at one side of the support engaging a side edge of the fabric material and bending the edge to assume a position at right angles to the bottom of the fabric material, and a second rotatable member at the side of the support, said second rotatable member engaging the right angular bent edge and bending it flat against the fabric material to form a fold.
2. In a machine of the character described, a support to receive a fabric material to be folded, a frame at one side of the support, a primary and a secondary pair of rollers journaled in the frame with an upper and lower roller in each pair, an endless feed belt disposed between the rollers, means on the belt adapted to grip one side of the fabric material, a vertical annular flange on the lowermost roller of the primary pair, said flange engaging the side edge of the fabric material and bending it to assume a vertical position, and a horizontally disposed annular flange cooperating with the secondary pair of rollers, said flange engaging the vertically bent edge of the fabric material and bending it to lie flat against the fabric material.
3. In a machine of the character described, a support to receive a fabric material to be folded, a frame at one side of the support, a primary and a secondary pair of rollers journaled in the frame

with an upper and lower roller in each pair, an endless feed belt disposed between the rollers, a horizontally disposed annular flange cooperating with the secondary pair of rollers, and means for driving the feed belt, the primary and secondary pairs of rollers, and the cooperating annular flange in unison.

4. In a machine of the character described, a support to receive a fabric material to be folded, a frame at one side of the support, a primary and a secondary pair of rollers journaled in the frame with an upper and lower roller in each pair, an endless feed belt disposed between the rollers, a plurality of pins on the upper face of the belt, said pins adapted to extend through interstices in the fabric material to grip and positively feed the fabric to be folded between the rollers, a vertical annular flange on the lowermost roller of the primary pair, said flange engaging the side edge of the fabric and bending it to assume a vertical position, and a horizontally disposed annular flange cooperating with the secondary pair of rollers, said flange engaging the vertically bent edge of the fabric and bending it to lie flat against the fabric.

5. In a machine of the character described, a support to receive a fabric material to be folded, a frame at one side of the support, a primary and a secondary pair of rollers journaled in the frame with an upper and lower roller in each pair, an endless feed belt disposed between the rollers, a plurality of pins on the upper face of the belt, said pins adapted to extend through interstices in the fabric material to grip and positively feed the fabric to be folded between the rollers, a vertical annular flange on the lowermost roller of the primary pair, said flange engaging the side edge of the fabric and bending it to assume a vertical position, a horizontally disposed annular flange cooperating with the secondary pair of rollers, said flange engaging the vertically bent edge of the fabric and bending it to lie flat against the fabric, and means for driving the feed belt, the primary and secondary pair of rollers and the cooperating annular flanges in unison.

6. In a machine of the character described, a support to receive a fabric material to be folded, a frame at each side of the support, a primary and a secondary pair of rollers journaled in each frame with an upper and lower roller in each pair, a pair of endless feed belts disposed one between each set of rollers, said feed belts having means for engaging the side edges of the fabric to be folded, a vertical annular flange on the lowermost roller of the primary pair of rollers, said vertical flanges engaging the side edges of the fabric and bending the fabric to assume a vertical position, and a horizontally disposed annular flange cooperating with the secondary pair of rollers on each side of the support, said horizontal flanges engaging the vertically bent edges of the fabric and bending said edges to lie flat against the edge of the fabric.

7. In a machine of the character described, a support to receive a fabric material to be folded, a frame at each side of the support, means for laterally adjusting said frames to receive fabric material of different widths, a primary and a secondary pair of rollers journaled in each frame with an upper and lower roller in each pair, a pair of endless feed belts disposed one between each set of rollers, said feed belts having means for engaging the side edges of the fabric to be

folded, a vertical annular flange on the lowermost roller of the primary pair of rollers, said vertical flanges engaging the side edges of the fabric and bending the fabric to assume a vertical position, and a horizontally disposed annular flange cooperating with the secondary pair of rollers on each side of the support, said horizontal flanges engaging the vertically bent edges of the fabric and bending said edges to lie flat against the edge of the fabric.

8. In a machine of the character described, a support to receive a fabric material to be folded, a frame at each side of the support, means for laterally adjusting said frames to receive fabric material of different widths, a primary and a secondary pair of rollers journaled in each frame with an upper and lower roller in each pair, a pair of endless feed belts disposed one between each set of rollers, said feed belts having means for engaging the side edges of the fabric to be folded, a vertical annular flange on the lowermost roller of the primary pair of rollers, said vertical flanges engaging the side edges of the fabric and bending the fabric to assume a vertical position, a horizontally disposed annular flange cooperating with the secondary pair of rollers on each side of the support, said horizontal flanges engaging the vertically bent edges of the fabric and bending said edges to lie flat against the edge of the fabric, and means for driving the feed belts, the primary and secondary pairs of rollers and the vertical and horizontal flanges in unison.

9. In a machine of the character described, a support to receive a fabric material to be folded, a pair of continuously moving members one on each side of the support, means on said members for holding the side edges of the fabric for movement longitudinally of the support, means on each side of the support for engaging the side edges of the fabric to bend said edges to assume a position at right angles to the body of the fabric, and other means at each side of the support for engaging the right angular bent edges and for further bending said bent edges to lie flat against the fabric to form a fold at each side of the fabric.

10. In a machine of the character described, a support to receive a fabric material to be folded, a pair of continuously moving members one on each side of the support, means on said members for holding the side edges of the fabric for movement longitudinally of the support, means on each side of the support for engaging the side edges of the fabric to bend said edges to assume a position at right angles to the body of the fabric, other means at each side of the support for engaging the right angular bent edges and for further bending said bent edges to lie flat against the fabric to form a fold at each side of the fabric, and means for laterally adjusting the support to receive fabric material of different widths.
